LOCOMOTIVE BODY

Edmund L. Izzi, Stamford, Conn., and Erle H. Hill and Basil A. Lee, Pittsburgh, Pa., assignors to Westinghouse Electric Corporation, a corporation of Pennsylvania

Application January 19, 1949, Serial No. 334

Term of patent 14 years

(Cl. D66—1)

To all whom it may concern:

Be it known that we, Edmund L. Izzi, Erle H. Hill and Basil A. Lee, citizens of the United States of America, residing, respectively, at Stamford, in the county of Fairfield and State of Connecticut; at Pittsburgh 6, in the county of Allegheny and State of Pennsylvania; and at Pittsburgh 18, in the county of Allegheny and State of Pennsylvania, have invented a new, original, and ornamental Design for a Locomotive Body, of which the following is a specification, reference being had to the accompanying drawing, constituting a part hereof:

Figure 1 is a plan view of a locomotive body, showing our design;

Fig. 2 is a view, in side elevation, of the locomotive body;

Fig. 3 is a view, in elevation, showing the front end of the locomotive body, and

Fig. 4 is an enlarged view, in perspective, of the locomotive body.

The appearance of the side of the locomotive body opposite to that shown in Fig. 2 is substantially the same as that shown in Fig. 2, and the appearance of the end of the locomotive body opposite to that shown in Fig. 3 is conventional.

We claim:

The ornamental design for a locomotive body, substantially as shown and described.

EDMUND L. IZZI.
ERLE H. HILL.
BASIL A. LEE.
